UNITED STATES PATENT OFFICE.

WILLIAM G. COUGHLIN, OF PHILADELPHIA, PENNSYLVANIA.

RAIL-JOINT SUPPORT.

Application filed May 2, 1925. Serial No. 27,540.

This invention relates to rail joint supports and more particularly to non-spacing rail joint supports and rail joint supports of the type adapted to extend over a plurality of ties for the purpose of more rigidly supporting a rail joint.

It is a general object of the present invention to provide a novel and improved rail joint support.

More particularly it is an object of the present invention to provide a rail joint support designed to support the bases of joined rails and maintain them in horizontal alignment when under load.

Another object of the present invention consists in the provision of a rail joint support adapted to distribute the weight of the rails and their load to a plurality of cross ties.

A further object of the present invention consists in the provision of a rail joint support provided with cushion means to reduce the injurious effects of hammer blows from wheels passing over the joint openings.

Still another object of the present invention consists in the provision of a rail joint support which avoids the necessity of spacing cross ties at the joint and which allows more latitude in the location of joints.

A still further object of the present invention consists in the provision of means, which will prevent the driving of the rails, by wedge action, thru the splice bars and of an anti-creeping rail joint which will prevent any longitudinal creeping of the rail in relation to either the ties or the joint support.

The above and further objects of the present invention will be more apparent to those skilled in the art after a consideration of the accompanying drawings and following specification, wherein is disclosed a single exemplary form of the present invention with the understanding, however, that various changes may be made therein by those skilled in the art, in the size, shape, design, arrangement, proportion, relation, and material of the various parts without departing from the spirit of the invention or the scope of the attached claims.

In said drawings;

Figure 1 is a plan view of a rail joint, the joint ties and a rail joint support constructed according to the present invention;

Figure 2 is a side elevation of the same;

Figure 3 is a longitudinal section thereof on line 3—3 of Figure 1;

Figure 4 is a transverse vertical section on line 4—4 of Figure 1;

Figure 5 is a perspective view of one end 60 of the rail joint support, the rails and cross ties being omitted;

Figure 6 is a perspective view of a portion 65 of a novel fish plate for use in conjunction with the joint support; and

Figure 7 shows respectively a plan and side elevation of a clip used in spacing the rails in relation to the sides of the joint support.

In the maintenance of railway track the 70 largest proportion of the labor is expended at the joints, which are the weakest part of the structure, largely because of the unsatisfactory splicing appliances and conditions.

In the rolling of all structural shapes, T-rails included, the object rolled must be placed in such a position that there is no "under-cut" of the rolls, i. e. no portion of an object rolled can be wider at a given point than it is at a point farther away from the center of the roll. It is therefore obvious that a T-rail cannot be passed thru the rolls in a vertical position, but on the contrary must pass thru practically flatwise and in so doing the hot metal of the ingot is pushed or crowded into that portion forming the head of the rail, which gets the greatest wear. This head therefore does not receive the direct pressure or manipulation necessary to furnish homogeneous and desirable material in it. Modern mill practice has developed a means of running the rails thru the rolls so that they can be set at a slight angle, producing a more direct pressure of the rolls on the head and base of the rail, thereby improving the quality of the material in these parts. This procedure necessarily results in increasing the angle of the under part of the head and the upper part 85 of the base, this angle ranging from 12° to 90 18° from the horizontal.

It is because of this feature of modern rails that the majority of the present day splice appliances are unsatisfactory. The inclination or slope of the under side of the head is considerably greater than the angle of repose, or the angle at which metal will slide on metal, and the result is that the sloping underside of the head of the rail under 105 the passage of heavily loaded trains acts as 110

a wedge to drive the splice bars apart, there ordinarily being no support under the base of the rail to prevent their deflection or being driven down thru the splice bars. Present day rail practice requires that the abutting ends of the joining rails be spliced midway between two ties so that the ends of the splice plates come above these ties to receive their support and thus the rail joint is supported from two ties rather than from one. The horizontal component of this thrust or wedge action is sustained by the splice bolts and the constantly applied and severe pressure elongates them, and this pressure and rapid vibration causes the nuts to become loose, thus further allowing the splices to be wedged apart by the rail driving down thru them, and consequently become ineffective.

With the splice thus impaired the load of passing trains is not distributed thru the rail to several cross ties but is concentrated on the first joint tie as the wheel nears the end of the rail and immediately on the second joint tie as the wheel reaches or touches the end of the adjoining rail and therefore these two ties are called upon to carry a very considerably greater load than the remaining ties, with the result that they settle in the road bed, forming a "low joint". These low joints not only produce uneven riding track but require a great deal of labor tamping the ties to obtain a true surface and constant tightening of the bolts to maintain the efficiency of the joint. The frequent tamping tends to crush and pulverize the ballast, forming a compact mass thru which water will not drain, and with the constant churning and pressure on these joint ties the ballast is turned into mud and a condition reached known as a "pumping joint". These "low" or "pumping joints" are not only a source of poor riding track and expense in their correction, but also of danger, as the uneven surface of the rails brings a jolt or jar under fast moving trains that throws undue stress on the rail at these points, causing many of them to fail. A large percentage of broken rails and rail failures occur at joints because of these conditions.

In rail renewals, either because of a change in the standard length of the rails, a slight permissible variation allowed the mills in rolling to a standard length, or a more accurate spacing at the joints for expansion and contraction due to temperature changes, the location of the joints of rails laid rarely, if ever, coincides with the location of the joints of the rail removed. It is therefore necessary to expend considerable labor in respacing the ties to fit the new joints with the disadvantage of changing their old and solid support on the roadbed, or to permit the new joints to come where they will, disregarding the location of the joint bars on the ties. In this latter event

it is highly probable that the ends of the two rails may be directly over a cross tie while the ends of the splice bars joining the same may be in the space between two cross ties, or perhaps the ends of the rails and the ends of the splice bars will be in the space between two ties.

With the above noted defects and difficulties in view the present device has been designed to support the rails at their base, to avoid the rails being driven thru the splice bars as a wedge, and to extend the support of the rail to two or more cross ties, thus giving the rails at the joints a greater support on the roadbed by being distributed over a greater number of cross ties, and consequently less likelihood of the latter settling in the ballast.

Referring to the drawings, there is disclosed at 10 and 11 a pair of rails abutting at 12, or rather being sufficiently spaced from each other at this point to allow for the necessary expansion and contraction due to temperature changes. These rail ends are adapted to be secured together by means of the fish plates or splice bars 13, which may be of any well-known form but are preferably of a special type to be later described. Their main function is to prevent relative transverse movement between the ends of the rails and to distribute the load from one rail to another and for this purpose they may be securely bolted to the webs of the rails by transverse bolts passing thru both of the splice bars and the web of the rail as is well-known.

To prevent the various difficulties mentioned in the above discussion the ends of the rails adjacent the joint are adapted to be supported by the rail joint support of the present invention, generally disclosed at 14. Broadly speaking, this comprises a channel or trough shaped member having a base 15 considerably wider than the bases of the rails which rest upon it, having vertical or upwardly extending sides or flanges 16 and down turned ends 17 on the base. The whole structure is formed of a single piece of metal bent or pressed into the desired shape. The base or bottom portion 15 is of such a length as to be supported preferably upon three cross ties, as shown in Figures 1, 2 and 3, and for this purpose is substantially flat, thus providing an adequate support upon the ties. For a distance somewhat less than the distance between the inner edges of the outside cross ties, and for a width less than the space between the vertical flanges 16, this base 15 is slightly raised above the remainder thereof of forming a step or seat 18 upon which the bases of the rails rest, and which is designed to prevent the weight caused by the deflection of the rail from being concentrated on the outer ties and to distribute it over all 130

of the ties supporting the plate. This raised seat or base 18 is also designed to act as a cushion or spring and by its resiliency to prevent damage to the rail from hammer blows of wheels passing over the joint openings. This raised seat or base may be given increased resiliency by providing it with transverse corrugations 19. These corrugations serve an additional purpose of providing additional strength against bending or buckling transversely of the plate.

The upwardly extending flanges 16 forming the sides of the trough are so shaped that their moment of inertia and section modulus, which determines the stiffness and strength of the plate, increase in the same ratio as the stress from the ends toward the middle, where these properties reach their maximum and at the point of maximum stress, this being accomplished by changing the area and shape of the section and volume of the metal by progressive steps or increments from the ends toward the middle, thus effecting a saving in material. Where it is not desirable to thicken the metal toward the center, owing to manufacturing difficulties, the increased metal may be provided by retaining the same thickness and making the width much greater, in which case the height may be reduced by folding over the widened portions as shown at 20.

The down turned ends 17, while not entirely essential to the operation of the device, add materially to its value in securing the plate against horizontal movement. These ends are adapted to abut against the outer sides of the outer ties as shown in Figure 3 and are perforated with elongated horizontal holes in order that bolts 17' may be passed thru these holes and extend approximately thru the neutral axis of the cross tie. To provide for gaging of the rails the ends of these down turned portions 17 are bent up at right angles, providing the ears or lugs 21 between which is adapted to closely fit the rectangular bar or washer 22 provided with two sets of holes adapted to fit over the bolts thru the cross tie, the holes being so arranged that in the four possible positions of the bar or washer the plate or joint support 14 will be bodily moved horizontally, this movement being allowed for by the elongation of the holes in the down turned ends 17.

Intermediate the ends of the base plate it may be provided with similar down turned portions 23 punched out from the base 15. These down turned portions 23 may be provided with similar ears or lugs 24 on their ends adapted to accommodate washers or plates 22 for the same purpose as the down turned ends 17. In addition they provide added transverse strength to the whole structure. If it is preferred the plate may

be made without the depending parts 17 and 23 and secured to the ties by the spikes that hold the rails in position.

The rails may be secured to the ties by spikes driven thru perforations 25 in the base plate but preferably are secured by clips 26 bolted down to the rail by bolts 27 extending upwardly thru the holes 25' in the base plate and provided with suitable lock washers and nuts. By referring to Figure 7 it will be seen that these clips comprise substantially square members 26 provided with a reduced neck 26" on either side thereof, which necks are square in cross section and joined by the sloping parts 26' to the square edges of the whole clip. A hole 28 passes thru the center of each clip but the reduced necks are eccentric to this hole so that by placing either side of the clip down in succession there are eight possible different distances from the side of the neck engaging the rail to the center hole thereby providing eight transverse adjustments for the rail. The holes are concentric in respect to the outer edges of the clips, which outer edges are thus always adapted to abut against the insides of the vertical flanges 16 of the joint support plate and as clearly shown in Figure 1 when the inner edges of the necks abut the bases of the rails the wider portions of the clips extend over the bases to hold them in position and the outer edges of these wider portions contact with the inner faces of the vertical flanges 16, thus positively spacing the rail in its desired position from the sides 16, which spacing is subject to eight adjustments by rotation and inversion of the clips as previously described. This adjustment further allows for the use of the rail joint support on curves and curved sections of rails for the adjustable feature of the clips together with their possible longitudinal arrangement owing to the provision of a large number of the perforations 25' allows for the accommodation of the curved rails between the flanges of the joint support. All of these adjustments provide for a proper gaging of the rails in addition to the gaging adjustments provided by the plates or washers 22 previously described.

The fish plates or splice bars which are particularly adapted to be used in connection with the present invention, but which may also be of general utility in connection with any type of rail joint, are designed to be reversible. They are best shown in Figures 4 and 6, where it will be noticed that the angle of the upper, inner, head supporting edge 30 is the same as the lower, outer edge 31, which in the position shown in Figure 4 is not in use. The diagonally opposite faces 32 and 33 are correspondingly inclined. These faces are so inclined to accommodate rails where the angle of the un-

derside of the head is different from the upper part of the base of the rail, where the splice bars engage these two parts, so that the inclined portions of the fish plates are in contact with the under side of the heads throughout their length and width and the corresponding condition occurs where they engage the upper faces of the bases. When wear occurs, which is brought about by hammer blows from the wheels crossing a small opening in the rails at the joints left for expansion and contraction purposes, the fish plates may be reversed and a new and unworn surface presented, thus providing an economical feature. The fish plates are, of course, built as double bulb beams having the narrow or thin web portion 34.

The splice bars or fish plates may be joined to the rails in the usual manner, by having bolts passing thru the holes 35 in the two fish plates and corresponding holes in the webs of the rails, but it is desirable in connection with the present invention to provide a plurality of holes 35' along the neutral axes of the upwardly extending side flanges 16 of the rail joint support to coincide with the various positions of the bolt holes in the webs of the rails and splice bars thru which bolts 36 may extend to secure both the rails and the fish plates in place to thus hold or anchor the rails against longitudinal movement or creeping. As shown in Figure 2, a number of these bolts with their heads 37 on the outside of the vertical flanges 16 project from either flange thru the rails and both fish plates and are provided with nuts 38 on the sides opposite from their heads. These may be sufficient to retain the fish plates in position but exert some side strain upon the vertical flanges 16 and to eliminate this it will be found desirable to thread the bolts 36 for a sufficient distance so that a lock nut may be placed thereon to engage with the fish plate not engaged by the nuts 38, and thus the fish plates may be clamped between two nuts to secure them very tightly in position and the bolt heads then serve only to prevent relative movement by the rails and the joint support.

Where the bolt holes in the rail webs are not in the center of the fishing space, the reversible fish plates are provided with two sets of bolt holes to permit them to be reversed. The center of each set of holes is to be spaced the same distance vertically from the center of the fishing space.

The joint support forming part of the present invention is not limited in its use to the particular type of fish plates just described, but any suitable fish plates to secure the rails is all that is ordinarily required altho any form of joint bars or splices that do not extend below the base of the rail may be used. Since the joint support is of such a

length as to be supported by two or more ties as may be desired, and where of a length to be supported by three or more ties, the conditions recited in the beginning of this specification, such as having the ends of the rails 70 and the ends of the splice bars in the same opening between two ties, where ties are not spaced after laying a new rail, is of no moment, as the load is still distributed to the several ties supporting the plate, and the expense and disadvantage of moving the cross ties from their old and solid support is eliminated.

The distance between the ends 17 is preferably equal to the usual spacing of ties. It 80 will be seen therefore that the joint support can thus be located anywhere and the rail joint allowed to come where it will and not necessarily in the center of the length of the support. The construction of the support is 85 such that it can be used not only at joints but anywhere along the rail length where added support is needed or desirable, or, in fact, can be used under the whole length of the rails.

Having thus described the invention, what is claimed as new and desired to be secured by Letters Patent is:

1. A rail joint support having a base materially wider than the base flange of a rail 95 adapted to rest on more than two cross ties, said support being so shaped that the section modulus increases in the same ratio from end to center as does the applied stress.

2. A rail joint support comprising a unitary structure having a base materially wider than the base flange of a rail and adapted to rest on at least three cross ties so shaped that the moment of inertia of transverse sections thereof increases from the 105 ends toward the center in the same ratio as the applied stress.

3. A rail joint support comprising a unitary trough shaped structure having a base materially wider than the base flange of a rail to be placed beneath a rail joint to support the same, said structure being so shaped and the material thereof so disposed that the moment of inertia and section modulus increases from the ends toward the center in 110 the same ratio as the applied stress.

4. A rail joint support including, in combination, a trough shaped structure adapted to support the bases of the joined rails, a base therefor adapted to rest on a plurality 115 of cross ties and means reinforcing said base transversely throughout most of its length and over at least one tie.

5. A rail joint support including, in combination, a trough shaped structure adapted to support the bases of joined rails, said trough being substantially wider than said bases, a base therefor adapted to rest on a plurality of cross ties and elevated transverse corrugations reinforcing said base.

6. A rail joint support including, in combination, a trough shaped structure adapted to support the bases of joined rails, a base therefor adapted to rest on a plurality of cross ties, elevated transverse corrugations on said base and flanges dependent therefrom for the purpose described.

7. A rail joint support including, in combination, a trough shaped structure adapted to support the bases of joined rails, an integral base therefor adapted to rest on a plurality of ties, an elevated seat on said base for said rails and means integral with said base adapted to be secured to the side of the tie.

8. A rail joint support including, in combination, a trough shaped structure adapted to support the bases of joined rails, a base therefor adapted to rest on a plurality of ties, a resilient elevated seat on said base for said rails, said seat being corrugated and means to space said rail bases from the sides of said trough.

9. A rail joint support including, in combination, a trough shaped structure adapted to support the bases of joined rails, a base therefor adapted to rest on a plurality of ties and a resilient elevated seat on said base for said rails, said seat being transversely corrugated.

10. In a rail joint support, in combination, a trough-shaped structure adapted to support the bases of joined rails including a base adapted to rest on a plurality of ties, side members spaced from said rails to allow clearance for the joining means, an elevated seat on said base for said rails and means to secure said rail bases directly to said seat.

11. A rail joint support including, in combination, a trough shaped structure adapted to support the bases of joined rails, a base therefor having an elevated portion, side flanges on said base spaced apart a distance greater than the width of said rail bases, means to secure said rail bases to said elevated portion of said trough base, including clips and bolts, said clips overlying said rail bases and positively spacing them from said side flanges and said bolts passing through said base only.

12. A rail joint support including, in combination, a trough shaped structure adapted to support the bases of joined rails, a base therefor, side flanges on said base spaced apart a distance greater than the width of said rail bases, means to secure said rail bases to said trough base, including clips, said clips overlying said rail bases, being bolted to the trough base and having eccentric necks and concentric flanges whereby to adjust said rail base from said side flanges.

13. The combination with a rail having a base and a joint support having a side member, of a clip having a flange provided with a central opening, the edge of said flange

being adapted to abut said side member, a neck on one side of said flange eccentric to said opening, said neck adapted to abut said rail base, said opening adapted to fit over a fixed stop about which said clip may be rotated.

14. In a rail securing clip, in combination, a neck, a flange extending laterally from one end of said neck beyond the edges thereof and eccentric thereto, a second neck on the opposite side of said flange and having a different eccentricity thereto, said clip having a hole therethru adapted to receive a bolt, said hole being eccentric to the edges of said necks and concentric to the edges of said flange.

15. In a rail securing clip, in combination, a pair of spaced necks, square in plan, a square flange between and projecting beyond the edges of said necks, said clip having a hole therethru equally spaced from each edge of said flange and being a different distance from each edge of each neck.

16. A rail joint support adapted to support the bases of rails joined by any ordinary splice bars or fish plates including in combination a one-piece base, side flanges projecting upwardly therefrom, a rail resting on said base spaced from said flanges and having perforations in the web thereof, perforations in said side flanges, and fastening means passing thru perforations of each part and preventing relative longitudinal movement between said joint support and the rail and maintaining the spacing of said rail from said flanges.

17. A non-spacing rail joint support adapted for use with any common type of splice bar and including a base, reinforcing flanges thereon, a rail joint on said base entirely spaced from said flanges, the rails thereof having perforated webs, holes substantially along the neutral axes of said flanges and bolts thru said holes and perforations to prevent relative longitudinal and transverse movement between the rails and support.

18. A non-spacing rail joint support including in combination with abutting rails and fish plates, a base beneath the rails, side flanges thereon having holes along their neutral axes, bolts passing thru said holes and the webs of said rails, said bolts securing the fish plates in position against said rails and preventing relative longitudinal movement between the support and rails.

19. In a non-spacing rail joint support, in combination, a base plate adapted to extend over and be supported by a plurality of ties, means to secure rails thereto with their joint anywhere along said base and means to secure said base to said ties substantially at their neutral axes.

20. In a non-spacing rail joint support, in combination, a base plate adapted to extend

over and be supported by a plurality of ties, means to secure rails thereto with their joint anywhere along said base, flanges depending from said plate and means to secure said flanges to the sides of cross ties substantially at their neutral axes.

21. In a non-spacing rail joint support, in combination, a base plate adapted to extend over a plurality of ties and be supported thereby, means to secure rails to said base plate, down turned ends on said plate, said ends having elongated openings therein, bolts passing thru said openings and thru the neutral axis of said ties to adjustably secure said plate to said ties for the purpose described.

22. In a non-spacing rail joint support, in combination, a base plate adapted to rest on a plurality of cross-ties, means to secure rails to said plate against movement transverse thereto, a depending flange on said plate, lugs on the ends of said flange, a perforated plate adapted to fit between said lugs, said flange being provided with elongated openings, and bolts passing thru said plate, flange and the neutral axis of a supporting tie, the holes in said plate being so spaced that lateral adjustment of said base plate may be effected to gauge the rails of a track.

23. In a non-spacing rail joint support, in combination, a base plate adapted to rest on a plurality of cross-ties, means to secure

rails to said plate against movement transverse thereto, a depending flange on said plate, lugs on the ends of said flange, a perforated plate adapted to fit between said lugs, said flange being provided with elongated openings, and bolts passing thru said plate, flange and the neutral axis of a supporting tie, the holes in said plate being so spaced that it may be reversed to effect lateral adjustment of said base plate.

24. In a non-spacing rail joint support, in combination, a base plate adapted to rest on a plurality of cross-ties, means to secure rails to said plate against movement transverse thereto, a depending flange on said plate, lugs on the ends of said flange, a perforated plate adapted to fit between said lugs, said flange being provided with elongated openings, and bolts passing thru said plate, flange and the neutral axis of a supporting tie, the holes in said plate being so spaced that it may be inverted to effect lateral adjustment of said base plate.

25. In a rail joint support, in combination, a base plate adapted to be supported by a plurality of cross-ties, side flanges thereon spaced from the rail joint, a raised rail seat narrower and shorter than said plate and means to secure said rail bases directly to said seat.

In testimony whereof I hereunto affix my signature.

WILLIAM G. COUGHLIN.
